[57] CLAIM

The ornamental design for the cup with lid, as shown and described.

DESCRIPTION

FIG. 1 is a perspective view of a cup with lid showing our new design;

FIG. 2 is a front elevational view thereof;

FIG. 3 is a top plan view thereof;

FIG. 4 is a bottom plan view thereof; and,

FIG. 5 is a cross sectional view thereof, taken along line 5—5 of FIG. 2.

A rear, a left side and a right side elevational views are identical with the front elevational view.
